US00D606544S

(12) **United States Design Patent**
Di Bari et al.

(10) **Patent No.:** **US D606,544 S**
(45) **Date of Patent:** **** Dec. 22, 2009**

(54) **CODED INFORMATION READER**

(75) Inventors: **Giuseppe Di Bari**, Rimini (IT); **Monica Alegiani**, Silvi (IT)

(73) Assignee: **Datalogic Scanning Group S.R.L.**,
Lippo Di Calderara Di Reno (BO) (IT)

(**) Term: **14 Years**

(21) Appl. No.: **29/322,183**

(22) Filed: **Jul. 30, 2008**

(30) **Foreign Application Priority Data**

Feb. 1, 2008 (EM) 000870761

(51) **LOC (9) Cl.** **14-02**

(52) **U.S. Cl.** **D14/428; D14/426**

(57) **CLAIM**

We claim the ornamental design for a coded information reader, as shown and described.

DESCRIPTION

FIG. 1 is front perspective view of a coded information reader of the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
